Specification for Design.

Patented Aug. 14, 1917.

Application filed May 12, 1917. Serial No. 168,287. Term of patent 14 years.

To all whom it may concern:

Be it known that I, ERNEST GINNETTI, a subject of the King of Italy, having declared my intention of becoming a citizen of the United States, residing at Washington, in the District of Columbia, have invented a new, original, and ornamental Design for Bottles, of which the following is a specification, reference being had to the accompanying drawing, forming part thereof.

Fig. 2 is a top plan view thereof.

I claim:

The ornamental design for a bottle, as shown.

ERNEST GINNETTI.
